UNITED STATES PATENT OFFICE

CHARLES W. GREEN, OF ILION, NEW YORK, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed May 17, 1923. Serial No. 639,569.

This invention relates to improvements in cash registers or accounting machines and has more particular relation to improvements in the locking devices employed therein.

5 An object of the present invention is the provision of means for selectively locking any totalizer or corresponding device against operation without interfering with the usual operation of others of such devices and the 10 provision of mechanism whereby the proprietor or other authorized persons can conveniently render such means ineffective.

Another object is the provision of an improved construction of a centralized locking 15 means for controlling the manner in which the machine is to be operated.

Still another object is to provide a secure and effective means for locking the various lids with which the machine is equipped, as 20 well as means for permitting a salesman or clerk to release a particular lid or cover and still prevent him from opening the remaining lids or covers, and an additional means for permitting the proprietor to release all the 25 lids, such releasing means being under the control of the centralized locking mechanism.

The improved machine is also provided with mechanism for accomplishing certain other functions when one of the lids, which 30 is under control of the proprietor, is opened, such as releasing a cabinet lid for exposure of the bank of item counters, operating a particular item counter, releasing the printing mechanism for taking totals accumulated by 35 the counters and locking the machine against operation while the machine is in this condition.

Still another object of the present invention 40 is to provide an effective means for preventing movement of the centralized locking lever from its adjusted position when one of the lids is in its open position.

With these and incidental objects in view 45 the invention consists in certain novel features of construction and combination of parts, the essential elements of which are set forth in appended claims, and a preferred form of embodiment of which is hereafter described with reference to the drawings which

accompany and form part of the specification.

Of said drawings:

Fig. 1 is a transverse sectional view of the machine to which this invention is applied showing the totalizers, totalizer actuating 55 mechanism and the devices for individually locking the clerks' keys as well as a portion of the lid-locking mechanism.

Fig. 2 is a plan view showing the arrangement of the various shafts which carry the 60 locking mechanism.

Fig. 3 is a transverse sectional view of the machine illustrating the centralized locking mechanism, part of the printer mechanism and the means for rotating the revolution 65 shaft.

Fig. 4 is a view in perspective illustrating in detail the various locking devices and co-operating parts.

Fig. 5 is a top view of the machine with 70 the printer and item counter lids broken away to show parts of the locking mechanism.

Fig. 6 is a view in perspective of the lower lid releasing mechanism as well as the means for locking the centralized locking lever in its 75 adjusted position while the lower lid is in its open position.

Fig. 7 is a detail showing the interlock between the front lid and the control lever.

In the accompanying drawings the improvements are shown in connection with a machine of the general type fully shown in the U. S. patents to Frederick L. Fuller, Nos. 1,729,338 and 1,742,401, granted Sept. 4, 1929, and Jan. 7, 1930, respectively. Only such 80 parts of the machine as are directly involved in the present invention are described herein, however, and reference should be made to the patents mentioned for any information desired as to the construction and operation of 85 the rest of the machine.

Although the improvements have been shown applied to the machine shown and described in the above cited patents, it is to be understood that the improvements are capable of being applied to or embodied in other forms of cash registers and accounting machines without departing from the spirit of 90 the invention.

Described in general terms the illustrated 100

machine comprises a series of manipulative devices such as keys 20 (Figs. 3 and 5) operable to actuate totalizing mechanism and mechanism for entering the items on a record strip. The keys 20 are pivoted upon a rod 21 and resting upon the rear ends of the keys is a key coupler 22 pivoted at 23. When the outer ends of the keys are depressed the coupler is rocked counter-clockwise about its pivot (as viewed in Fig. 3) and its nose 24 enters the notches 25 in the rear ends of the keys. The construction and purpose of key coupler mechanisms are well known in the art and need not be discussed herein.

15 As shown in Fig. 3 each key 20 is formed with an upwardly extending arm 26 carrying a stud 27 engaging a slot 28 in a plate 29 rigidly mounted in a frame 30 loosely mounted on the shaft 31. The slots 28 in plates 29 are 20 graduated so that each of the keys will impart a different degree of movement to the frame 30. The plates are furthermore provided with arcuate slots 36 to permit the upward tilting of the cam plates without interfering with the studs on the remaining unoperated keys. Secured to the frame 30 is a 25 segmental rack 311 (Fig. 1). It is to be understood that the keys 20 are arranged in banks and that for each bank there is a 30 differentially actuated frame 30 and its corresponding segment rack. Each segment is always in mesh with a pinion rigid with its corresponding item type wheel 32 and sets up a number which corresponds to the value of 35 the key depressed.

Connected to the key coupler 22 is a double rack 37 (Fig. 3), the connection being such that as the coupler is rocked by the keys the rack is raised or lowered, and drives a gear 38 40 secured to shaft 39 in such a manner that a complete reciprocation of the coupler will effect a complete rotation of the shaft. The shaft 39 carries cams and other devices for operating various parts of the mechanism. 45 The mechanism for effecting rotation of the shaft has not been shown or described in detail because it is old and well known in the art.

50 In Figures 1 and 5 there are shown two keys 40 and 41 which are designated as "clerks" or "coupler lifting keys". These keys, which are preferably located at the extreme left of the keyboard, have certain functions, one of which is to serve as a means 55 whereby the key coupler 22 may be partially raised to what may be termed the coupling position, in which position other keys representing the nature and amount of the transaction may be engaged with the coupler so 60 that a complete operation of all the keys so engaged with the coupler may be effected by pressure applied to any one of such engaged keys.

65 The means whereby the coupler 22 is lifted to the coupling point comprises a coupler

lifting cam surface 42 (Fig. 1) formed on the rear end of each of the clerks' keys 40 and 41 and cooperating with a face 43 on a shoulder on the coupler 22 to lift the coupler until the portion 431 of the shoulder on the key coupler 70 strikes the portion 432 on the key and stops the motion of the key and key coupler. The coupler is retained in its lifted position by the usual spring pressed pawl 441 (Fig. 3) engaging the teeth of a ratchet wheel 45 secured to the extreme right hand end of the rotation shaft 39. When the key coupler has been 75 so lifted and held, depression of the amount keys 20 will cause the notches 25 therein to engage spring pressed plates 433 on the 80 coupler.

85 Mounted below the item type carriers 32 previously mentioned and operable by the segmental racks 311 are two totalizers designated as totalizers "A" and "B" in Fig. 1 of the drawings. These may be utilized for the purpose of registering amounts for separate departments or clerks or to segregate the 90 transactions in any other two classes, and they have manipulative means associated therewith in order that either totalizer may be operated to register amounts of the various 95 transactions.

100 Totalizers "A" and "B" are pivotally mounted between side frames so that their pinions are capable of being rocked into engagement with their respective actuators. The engagement of the totalizer "A" with its actuator is under control of its corresponding clerk's or coupler lifting key 40 while the totalizer "B" is placed in operation by means 105 under control of its associated clerk's or coupler lifting key 41. The engagement of the totalizer pinions with their associated actuators is effected during the time that the clerk's or coupler lifting key is being depressed to its coupling position. Other keys may now be engaged with the coupler and upon further depression of one or more of 110 such other keys the pinions will be actuated an amount commensurate with the value of the key or keys depressed. At the extreme end of the downward stroke, or, if desired during the first part of the upward stroke of the keys, the selected totalizer is disengaged 115 from the actuators and remains disengaged during the time the keys are returning to their normal position. The totalizer engaging and disengaging mechanism is not involved in the present invention and for a detailed description and showing reference 120 may be had to the above mentioned Patent 1,742,701.

125 As has been just stated, the entering of items into the totalizers is directly controlled by the clerks' keys and in practical use each clerk is assigned a particular totalizer and corresponding clerk's key so that the proprietor is able to ascertain the amounts of sales 130 of the respective clerks operating the ma-

chine and by simply adding together the amounts of the sales of the clerks the aggregate amount of business transacted by all the clerks during a particular period may readily be obtained.

In this particular type of machine where multiple totalizers are employed it is especially desirable that, in the absence of a certain clerk, the particular key assigned to that 10 clerk shall be locked against operation in order to prevent fraudulent and improper manipulation of the machine.

One practical method for accomplishing the intended results is to provide the machine 15 with locks which directly control the operation or non-operation of the clerks' keys, each clerk, of course, being supplied with a key corresponding to the particular lock assigned to him. By means of this locking system 20 each clerk is enabled to have entire control of his totalizer and when he goes off duty he is enabled to lock the key and totalizer assigned to him against operation and still allow the other clerks to operate their respective keys and totalizers in the usual manner.

The present invention is preferably used in connection with a cash register having multiple drawers so that there may be a drawer and corresponding totalizer for each 25 clerk. When this arrangement is used in connection with the locking system just explained each clerk will be directly responsible for the amount of sales transacted by him and is answerable to the proprietor for any 30 discrepancy existing between the cash in his particular drawer and the amount standing on his corresponding totalizer.

As a precaution against one clerk surreptitiously operating a clerk's key not assigned 40 to him the following mechanism, which is best shown in Figs. 1, 4 and 5, is provided. Secured by any desirable means to the upper front of the enclosing cabinet are two locks 44 of the conventional type, the barrels of the 45 locks projecting through the said cabinet to facilitate insertion of the keys of the respective locks. Mounted adjacent the clerk's keys are levers 45 the upper ends of which are held in engagement with the bolts of their respective locks by springs 46. The lower arm 50 of each lever is provided with a hook 48 and an arcuate slot 49 the purpose of which slot will be explained hereinafter. Each clerk's key is further provided with a pro- 55 jection 491 (Fig. 1). Normally, that is when the bolt of any lock is withdrawn, the projection 491 will be out of the path of the upper edge of the hook 48 and the clerk's key may be operated in the regular manner; but when- 60 ever the clerk desires to lock his operating key, he inserts his key in the corresponding lock and projects the lock bolt, thereby bringing the upper edge of the hook 48 under the stud 491 and preventing operation of the cor- 65 responding clerk's key. It will be evident

that this will have no effect upon the other clerk's key and that the other clerk on duty can operate his key and totalizer in the usual way.

As so far described it is obvious that if all the clerks happened to be off duty at a particular time the machine would be locked against operation and the proprietor would be unable to depress the keys and operate the mechanism in the usual manner without using duplicate lock keys. To give the proprietor a more convenient control over the clerks' keys the following mechanism is employed.

Pivottally mounted upon the key shaft 21 is a bell crank 50 (Figs. 1 and 4) the arm 51 of which is provided with a stud 52 sufficiently long to engage shoulders 53 formed on the lower arms 47 of the locking levers 45. Directly underneath the key shaft 21 and journaled between the side frames is a shaft 54. Secured to the left end of the shaft is a cam 55 in the path of the lower arm of the bell crank 50. When the shaft 54 is rotated, the stud 52 contacting with the shoulders 53 of the locking levers 47 forces the locking levers forwardly until the arcuate slots 49 are in the path of the studs 491 carried by the clerks' keys. When the parts are in this position the clerks' keys may be depressed irrespective of whether the bolts of the clerks' locks have been projected. The means for rotating the cam 55 to accomplish the results set forth is under control of the proprietor only and will be presently described.

The machine disclosed in the Fuller Patent 1,742,701, to which the invention is applied, has mechanism which controls the manner in which the machine is to be operated, as well as other functions such as locking the register, releasing the drawers, conditioning the machine for printing totals and resetting the totalizers and counters. This mechanism comprises a pointer 552 and lock 551 under control of the proprietor and situated at the right hand end of the machine (see Fig. 5).

When the pointer 552 is adjacent the words "lock register" the machine is locked against operation. When the pointer is adjacent "closed drawer" the machine is conditioned so that it cannot be operated unless the drawer is closed. When the pointer is set in the "open drawer" position the machine is conditioned so that it can be operated while the drawer is open. The mechanism for accomplishing these results is not involved in the present invention, and for details of construction reference may be had to Patent 1,742,701.

When the index is set opposite "Unlock A & B" the locked clerks' keys are released for operation. The means for accomplishing this will now be explained in detail. Loosely mounted upon the shaft 31 is an adjustable bell crank 56 (Figs. 3 and 4) and secured to the said bell crank is a curved plate

57. The plate carries the pointer or index 552 which moves over a scale 59 (Fig. 5) secured to the cabinet upon which is engraved or printed the above-mentioned or other suitable characters. Directly beneath the plate 57 is a second plate 60 (Fig. 3) secured to the side frame of the machine, the extensions 61 of which co-operate with suitable slots formed in downwardly extending projections 62 integral with the adjustable plate 57 thus guiding the plate 57 in its movement.

Fastened to the adjustable plate 57 by any desirable means is the lock 551, the barrel of which projects through and is capable of moving in an elongated slot 610 (Fig. 5) formed in the cabinet of the machine. The rotatable bolt of the lock is provided with a flange 58 (Fig. 3) capable of registering with a series of notches 63 formed on the plate 60. The flange 58 is further provided with a slot so arranged and constructed that when the bolt is rotated by manipulation of the inserted key the said slot and plate 60 are placed in alinement and the bolt and parts carried thereby are released for adjustment. When the pointer is set to the desired position the key and bolt are again rotated so that the flange 58 of the bolt cooperates with the proper notches 63 whereby the adjusted bell crank will be locked against movement when the key is withdrawn.

For aligning the bell crank 56 a spring urged pawl 64 pivoted upon the bell crank 56 is provided. The pawl 64 engages notches 65 formed upon the lower edge of the plate 60 to hold the adjustable bell crank in its set position.

The lower arm of the bell crank 56 is provided with an extending sector arm 66 (Figs. 3 and 4) carrying teeth 67. Mounted loosely on the key shaft 21 is a gear sector 68 meshing with the teeth 67 of sector arm 66 and secured to the gear 68 is a somewhat larger gear sector 69 meshing with a gear sector 70 secured to the right hand end of the shaft 54 hereinbefore mentioned. From the foregoing it is evident that when the proprietor manipulates the bell crank 56 so that the index is adjacent "Unlock A & B" the shaft 54 will be rocked by means of the train of mechanism just described, to actuate the cam 55 to disable the locking levers 45 for release of any locked clerks' keys.

In the Fuller Patent 1,742,701 there is provided a suitable printing mechanism for printing upon a record strip the amount, nature of the transaction and a special character identifying the clerk operating the machine. The printing mechanism of the present application is pivotally mounted upon the shaft 31 and is capable of being rocked forwardly over the respective totalizers "A" and "B" in order that the amount standing thereon can be printed upon the record strip. The machine is further pro-

vided with the so called autographic feature, or a device whereby a written entry may be made to identify the same with some particular sale or person. (See Fig. 5.)

The printing mechanism is not fully disclosed in this application but a part of one of the pivoted frames thereof is shown at 701 (Fig. 4) and the record strip is shown diagrammatically in Fig. 3, reference character 75 indicating the supply roll and 76 the storage roll, the direction of the feed being designated by the arrows. The supply and storage rolls are mounted upon a separate frame which is pivoted upon the side frame 701 of the printer mechanism so that this separate frame may be swung around its pivot to an upward position for replenishing the paper supply or removing the printed record strip. Directly over the printing mechanism and record strip is a flat lid or writing table 78 (Figs. 1, 3 and 5) hinged at its rearward end and provided with a glass 79 through which printed items are visible. The glass is further provided with a writing slot 80 to permit the entering of the notations adjacent the printed items. By lifting up this lid access may be had to the printer when it is necessary to replenish the supply of paper.

Located in the central part of the machine and directly over the keys 20 is a second lid 82 (Figs. 1 and 5) hinged at its lower end. This lid is equipped with a shield or cover 83 overlying the totalizers. It is desirable, of course, to have the locks so constructed that a clerk may be able to open the writing table lid 78 for replacing the record strip, but he should be unable to open the lid 82 which would give him access to the totalizers. The details of the novel mechanism devised to accomplish the desired results will now be set forth.

Suitably journalled between the side plates of the front lid 82 is a rock shaft 85 (Figs. 1 and 5) secured to the extreme ends of which are two locking spiders 86 and 87 urged rearwardly by spring 951. Each spider comprises an upwardly extending hook 88 engaging a locking lug 89 secured to the upper lid 78 and a downwardly extending hook 90 engaging a transversely extending lug 91 carried by the cabinet proper. As is evident from Fig. 1, the hook 88 is somewhat shorter than the hook 90 so that if the spiders are rocked a short distance they will permit the opening of the upper lid, but the hook 90 will not have been released from the locking lug 91, and will not, therefore, permit opening of the lower lid 82. For the purpose of permitting this partial rocking of the locking spiders there is secured to the shaft substantially midway a releasing finger 92 (Fig. 5) suitably disposed underneath a bolt of a lock 93. The travel of the bolt is sufficient to actuate the releasing finger 92 to rock shaft 130

85 to withdraw the hook 88 but not sufficient to withdraw the hook 90. It will be clear that the clerk or whoever is provided with the key of the lock 93 will be able to gain access 5 to the upper lid to replenish the paper supply, etc., but cannot obtain access to the totalizers or to the printing mechanism to obtain the totals standing on the totalizers. The spider 87 is provided with a nose 94 which will engage 10 a stud 95 and prevent further rocking of the spider 87, shaft 85 and parts carried thereby.

At the end of the day's business or any other desired period the proprietor opens 15 both of the lids just referred to, obtains the totals accumulated on the totalizer and then resets the same to zero. The means whereby the proprietor can accomplish the above is under control of the lock 551 above mentioned.

The index is set opposite adjacent the word "reset" and through the medium of sector 66, gears 68, 69 and 70 the shaft 54 is rocked counter-clockwise as viewed in Fig. 1. 25 Shaft 54 has secured thereto a disk 97 (Figs. 1 and 4) formed with a cam slot 98 in which registers a stud carried by a bell crank 99. When the index is set to the "reset" position, the bell crank 99 will be moved rearwardly 30 by the train of mechanism just described to bring the stud 95 into a notch 100 simultaneously rotating the spiders 86 and 87 sufficiently far enough to unlock both lids.

When the lower lid is opened certain mechanism 35 comes into play whereby the latch for the special counter lid is released, the counter for indicating the number of times the lower lid is opened is actuated, the printer frame is released for obtaining totals, the operating mechanism is locked against movement and the centralized locking mechanism is prevented from being moved from "reset" position as long as the lower lid is in its open 40 position. The mechanism for accomplishing all this will now be taken up in order.

Extending transversely between the side frames and suitably journaled in lugs 101 (Fig. 1) is a shaft 102, (see also Fig. 4) and in longitudinal alinement with the said shaft 50 is a second shaft 103 journaled in a similar manner. Shaft 103 terminates at a point 104 (Fig. 2) but is capable of rotating with the shaft 102 by means which will presently be described. The shaft 102 carries a plate 105 having a cam slot which registers with a stud 1051 (Fig. 3) carried by an arm secured to the lower lid 82 so that as the lid is reciprocated the shafts will be rocked simultaneously.

60 In registers of this class it is usual to provide item counters for counting the number of times certain operations and transactions are performed. An item counter is provided in the present machine for indicating the number of times the lower lid is opened. This

counter and the other counters mentioned for counting the various kinds of operation of the machine are covered by a suitable lid hinged to the cabinet, the counter lid being opened each time that the lower lid is opened. 70 The counter lid 106 is shown in Fig. 5 and the counter and part of the operating lever is illustrated in Fig. 1. A latch 107 urged forwardly by a spring 108 (Fig. 4) is loosely mounted upon shaft 102. A pin 109 secured to the latch 107 is urged forwardly by the said spring 108, so that it contacts with the edge of an arm 110 secured to the rock shaft 102. From this it is evident that whenever shaft 102 is rocked by opening the lower lid 82 the latch 107 will be retracted to release the special counter lid. 75

For actuating the counter 1110 (Fig. 1) there is provided a link 111 articulated to the operating arm 110 and slidably mounted at 80 its rearward end. The rearward end of link 111 has suitable connections to an item counter 1110 (Fig. 1) of a conventional type so that each time the lower lid 82 is opened a unit is added to the item counter. 85

As has been explained heretofore, in order to print the totals standing on the totalizers the printer frame is rocked forwardly over the respective totalizer. When in this position a platen will be actuated by a hammer 90 so that the total accumulated on the totalizer will be printed upon the record strip. Normally, that is when the lower lid 82 is closed, the printer frame will be locked against such movement. 95

The printer frame 701 is equipped with a stud or projection 112 (Fig. 4) which normally has in its path an obstructing arm 113 secured to rock shaft 103. A spring 114 interposed between the arm 113 and another arm 115 secured to the shaft 102 draws the arm 113 downwardly so that its lower edge contacts with a lug 116 formed on a projection of the arm 115. From this it is evident that the shafts 102 and 103 may be rocked simultaneously or if shaft 103 is held immovable for any reason whatsoever, the rock shaft 102 could be rocked independently. The reason for the flexible connection between the two shafts will appear later. From the foregoing it is clear that whenever the lower lid 82 is opened and the arm 113 is rocked downwardly to clear the projection 112 the printing mechanism is free to be rocked forward for printing the totals on the record strip. 110 115

While the totals are being printed it is very desirable that the keys be locked against operation. This is performed by an arm 117 secured to the extreme end of shaft 103 (Fig. 4), which moves downwardly in the path of a projection 118 integral with the coupler 22 whenever the lower lid 82 is opened, thus locking the keys and operating mechanism against operation. 120

The forward edge of the arm or projec- 130

tion 118 is concentric with respect to shaft 103 and whenever the machine is operated the coupler 22 will be lifted and the arm 118 will pass under the arm 117. If for any reason the coupler should be held upwardly by a partial depression of any keys and if the shafts 102 and 103 were integral, access to the lower lid would be prevented since the plate 105 would be locked. By virtue of the flexible connection between the shafts 102 and 103 the lower lid may be opened during the time the operating keys are displaced from their normal position. This facilitates the release of the operating mechanism in the event that the parts should become jammed during an operation of the keys, and if it were not for this feature it would be necessary to remove the cabinet to gain access to the mechanism.

The reciprocating of the lower lid to its open position will also lock the centralized lock mechanism against adjustment from its "reset" position. The devices for accomplishing this are best shown in Fig. 6, the lid being illustrated in its open position. Secured to or integral with the shield 83 is a plate 120 the latter being provided with forward and rearward extensions 121 and 122 respectively at substantially right angles to the said plate 120. The upper edges of the extensions are substantially concentric with the hinges of the lid 82 and when the latter is open these edges are slightly above the line of travel of a lug 123 formed upon the upper end of the bell crank 99. Therefore when the lower lid is opened as clearly shown in Fig. 6, the lug 123 is to the rear of the extension 122 thus locking bell crank 99, and through the connections previously mentioned preventing movement of the centralized locking element 56. As the lid is moved to its rearward or closed position the rear end of extension 122 back of the concentric edge will force the bell crank slightly to the rear. The concentric edge will then pass under and in contact with member 56 and lock this member against movement until the lid is completely closed. When the lid is completely closed and the control lever is out of the resetting position the lug 123 is directly over the extension 121 as shown best in Fig. 1 of the drawings. Therefore when the centralized locking member is in any other position than "reset" the lug 123 overlying the extension 121 will also serve as a very effective lock against any fraudulent opening of the lower lid 82 by unauthorized persons. It is understood, of course, that when the machine is placed in the "reset" condition the bell crank 99 will be moved rearwardly so that lug 123 clears the extension 121 thus releasing the lower and upper lids in the manner previously described.

Fig. 7 illustrates quite clearly the relative position of the parts just referred to at

various stages in their operation. Normally the lug 123 is in the broken line position indicated in this figure, while the plate 120 and lid 82 are in the position shown in full lines, wherein the co-operation of the forward end of extension 121 with the lug 123 prevents opening of the lid. Movement of the element 57 to the "reset" position will place the lug 123 in the full line position shown, wherein it will not interfere with the rocking of the extensions 121 and 122 and hence the opening of the lid 82. On the other hand, when the latter is opened the extensions 121, 122 will be in the broken line position indicated and it will not be possible to return the lug 123 to its broken line position so that the element 57 will also be locked.

It is thought that the operation of the devices is set out in such detail in the foregoing description as not to require the usual summary of the operation of the machine.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What is claimed is:

1. In a machine of the class described, a plurality of totalizers, a plurality of totalizer selecting keys, a plurality of individual lock controlled members adapted to selectively prevent operation of said keys, and a separate single lock controlled element for simultaneously operating all of said members to release said keys.

2. In a machine of the class described, the combination of a plurality of keys, common operating means controlled by said keys, members one for each key normally allowing operation of its related key, separate and independent means controlled by lock and key for placing said members in a position to lock their related keys, and additional means whereby a member that has been placed in key-locking position may be removed therefrom to allow depression of the related key.

3. In a machine of the class described, the combination of a series of accounting devices, a series of keys for controlling said accounting devices, common operating means controlled by said keys, means controlled by lock and detachable key for preventing operation of the keys and accounting devices, and separate means for disabling the first mentioned means.

4. In a machine of the class described, the combination of a series of accounting devices, a series of keys for controlling said devices, common operating means controlled by said keys, a plurality of means under lock and detachable key, one for each of said series of

- keys for preventing operation of each key and accounting device related thereto, and separate means for simultaneously disabling all of said plurality of means. 5. In a machine of the class described, the combination of a plurality of accounting devices, a plurality of keys for controlling said accounting devices, common operating means controlled by said keys, means controlled by lock and detachable key for preventing operation of the keys and accounting devices, and separate lock-controlled means whereby a key and corresponding accounting device may be freed from the control of said operation-preventing means. 6. In a cash register, the combination with a series of keys, a series of accounting devices controlled thereby, common operating means controlled by said keys, a series of members each adjustable to control the operation of a related key and accounting device, a projection carried by each key, and separate means each controlled by lock and detachable key and associated with one of said members for bringing the adjustable member in the path of the said projection on one of said keys to prevent operation of the related key and accounting device. 7. In a machine of the class described, the combination with a series of accounting devices, a series of keys for controlling said devices, common operating means controlled by said keys, a series of adjustable members each related to a key to control the operation of the key and an accounting device, a projection carried by each key, separate means under lock and detachable key for bringing each adjustable member in the path of the projection on a related key to prevent operation of said key, and connections to separate and independent means for withdrawing the adjustable members out of the paths of said projections. 8. In a cash register, the combination with a series of keys, accounting devices controlled thereby, common operating means controlled by said keys, adjustable members, one related to each key and normally allowing operation of the keys but movable to two other positions, means for moving each member to one position under control of a lock and detachable key for preventing operation of its related key and accounting device, and means for moving said members to a second position whereby they will unlock said keys. 9. In a cash register, the combination with a series of keys, accounting devices controlled thereby, common operating means controlled by said keys, an adjustable member related to each key normally allowing operation of the key and movable to two other positions, means for moving each member to one position under control of a lock and detachable key for preventing operation of its related key and accounting device, and means for moving said members to a second position whereby they will unlock said keys. 10. In a cash register, the combination with a series of accounting devices, a series of keys for controlling said devices, common operating means controlled by said keys, a corresponding series of members movable by separate locks and detachable keys to an intermediate position for preventing operation of the keys and accounting devices, and separate and independent means for placing said members in two positions wherein operation of the keys will be permitted. 11. In a cash register, the combination with a series of accounting devices, a series of keys for controlling said devices, common operating means controlled by said keys, a corresponding series of members movable by separate locks and detachable keys to an intermediate position for preventing operation of the keys and accounting devices, and separate and independent means for placing said members in two other positions wherein operation of the keys will be permitted, the movement of members to one of said two positions being under control of a separate and independent lock and detachable key. 12. In a machine of the class described, the combination with a series of keys, common operating means controlled by said keys, a plurality of adjustable members one for each key normally allowing operation of its related key, separate and independent means controlled by lock and key for placing said members in a position to lock their related keys and separate and independent means for moving all the adjustable members to a position to allow depression of all the keys irrespective of whether they have been placed in a locking position. 13. In a machine of the class described, the combination with a series of keys, common operating means controlled by said keys, a plurality of adjustable members one for each key normally allowing operation of its related key, separate and independent means under lock and key for placing said members in a position to lock their related keys and separate and independent means for moving all the adjustable members to a position to allow depression of all the keys irrespective of whether they have been placed in a locking position, the last means being under control of an independent lock and detachable key. 14. In a machine of the class described, the combination with a plurality of keys and accounting devices, a plurality of lock-controlled devices one for each key for controlling the operation of each key and accounting device and means whereby one of said lock

controlled devices may be thrown out of action regardless of the condition of its lock.

15. In a machine of the class described, the combination with a plurality of keys and accounting devices, a plurality of lock-controlled devices one for each key for controlling the operation of each key and accounting device and a single lock controlled means for disabling all the lock-controlled devices.

16. In a machine of the class described, the combination with a plurality of keys and accounting devices, a plurality of lock-controlled devices one for each key for controlling the operation of each key without affecting the operation of the remaining keys and a supplemental means for rendering all the locked lock-controlled devices ineffective.

17. In a machine of the class described, the combination of a key, a projection carried by said key, a lock controlled adjustable member movable in the path of said projection to prevent depression of said key and a separate and independent lock-controlled device for moving said member still further out of the path of said projection to allow depression of the locked key.

18. In a machine of the class described, the combination with a cabinet, a lid attached thereto, an item counter, lock-controlled means for unlocking the lid, a second lid normally concealing said counter and separate means under control of the first lid for releasing the second lid to permit exposure of the counter and simultaneously actuating the item counter.

19. In a cash register, the combination with a cabinet, a series of recording elements, a printer adjustable for taking impressions from said recording elements but normally prevented from taking such impressions, a normally locked lid attached to the cabinet, means for releasing the lid and connections with the lid whereby the printer is released for taking printing impressions when the lid is opened.

20. In a cash register, the combination with a cabinet provided with a lid, an operating mechanism, a shaft connected to be rocked when the lid is opened, a second rock shaft carrying an arm for locking the operating mechanism when the lid is opened and a flexible connection between the two shafts whereby the first rock shaft may be rocked to release the lid when the second rock shaft and arm is held against movement.

21. In a cash register, the combination with a cabinet provided with a lid, normally locked adjustable means for unlocking the lid when adjusted to one position and means carried by the lid for preventing movement of the adjustable means out of said position when the lid is in its open position.

22. In a cash register having item counters, a plurality of totalizers, a printing mechanism and totalizer selecting keys, separate

covers for the item counters, the totalizers and the printing mechanism, said covers being normally locked against access, individual locks operable to prevent operations of the totalizers selecting keys, a device manually adjustable to different positions, means rendered effective when said device is adjusted to one of its positions for controlling the unlocking of all of said covers and rendering the locks for the totalizer selecting keys ineffective, and a lock for preventing unauthorized operation of the manually adjustable device.

23. In a cash register having item counters, a plurality of totalizers, a printing mechanism and totalizer selecting keys, separate covers for the item counters, the totalizers and the printing mechanism, locks normally preventing opening of said covers, individual locks for preventing operation of the totalizer selecting keys, a device manually adjustable to different positions, mechanism rendered effective by adjustment of said device to one of its positions for disabling a plurality of said cover and totalizer selecting key locks, devices rendered effective by opening one of the covers for preventing movement of the manually adjustable device away from the one position above mentioned and for releasing another of said covers, and key operated locking devices for preventing unauthorized operation of the manually adjustable device.

24. In a cash register, the combination with a cabinet provided with a lid, type-carrying means, an operating mechanism, a printer mechanism adjustable for taking impressions from said type carrying means but normally prevented from taking such impressions, and means operated by the lid for simultaneously locking the operating mechanism and unlocking the printer mechanism for taking printing impressions.

25. In a cash register, the combination with a totalizer, of means normally preventing access to said totalizer but adjustable for exposing the same, operating mechanism including a key-coupler, and means controlled by the first-mentioned means for locking said key-coupler when said first-mentioned means is adjusted to a position for exposing said totalizer.

26. In a machine of the class described, the combination of a normally locked hinged lid, a shiftable control member for unlocking said lid, a lock for said control member, a second normally locked lid, and separate means including a cam operated shaft under control of the first lid for releasing the second lid.

27. In a cash register having item counters, a plurality of totalizers, a printing mechanism and totalizer selecting keys, separate normally locked lids for the item counters, the totalizers and the printing mechanism, individual locks for preventing operation of the totalizer selecting keys, and a common mechanism operable to control the unlocking

of all of said lids and free the totalizer selecting keys for operation.

28. In a cash register, the combination with a cabinet provided with a lid, an operating mechanism, printing mechanism, said printing mechanism being operable only when the lid is open, and means actuated by the lid for locking the operating mechanism when the lid is opened.

19 29. In a cash register, the combination with a cabinet provided with a pivoted lid, printing mechanism controlled by said lid, an operating mechanism, a locking means for said operating mechanism, and means operated by said lid for actuating said locking means to operative and inoperative positions.

30. In a cash register, the combination with a cabinet provided with a lid, a first and a second mechanism operable at different times under the control of the lid, means for locking the first mechanism while the lid is closed, and means for locking the second mechanism while the lid is open.

In witness whereof I have signed my name
25 this 15th day of May, 1923.

CHARLES W. GREEN.
